DESIGN FOR A SUGAR BOWL

R. Guy Cowan, Syracuse, N. Y., assignor to Onondaga Pottery Company, Syracuse, N. Y., a corporation of New York

Application October 7, 1935, Serial No. 58,868

Term of patent 14 years

To all whom it may concern:

Be it known that I, R. Guy Cowan, a citizen of the United States, residing at Syracuse, in the county of Onondaga and State of New York, have invented a new, original, and ornamental Design for a Sugar Bowl, of which the following is a specification, reference being had to the accompanying drawing, forming part thereof.

In the drawing:

I claim:

The ornamental design for a sugar bowl substantially as shown.

In testimony whereof, I have hereunto signed my name, at Syracuse, in the county of Onondaga, and State of New York, this 30th day of September, 1935.

R. GUY COWAN.
